INVENTOR.

John Joshua Miller

UNITED STATES PATENT OFFICE.

JOHN JOSHUA MILLER, OF SAN DIEGO, CALIFORNIA.

ORNAMENTAL REINFORCED-CONCRETE VENEER.

1,072,760.

Specification of Letters Patent. Patented Sept. 9, 1913.

Application filed May 24, 1912, Serial No. 699,548. Renewed July 24, 1913. Serial No. 781,037.

To all whom it may concern:

Be it known that I, JOHN JOSHUA MILLER, a citizen of the United States, residing at San Diego, in the county of San Diego and State of California, have invented an Improved Ornamental Reinforced Concrete Veneer, of which the following is a full and exact description.

This invention relates to a concrete veneer which may be applied in the construction of concrete walls and the like, its objects being the provision of means for making the outer sides of the wall of a finer material and texture, whereby the wall may be given a finished appearance which imitates natural stone, or may be finished in relief designs, at a slight additional cost, the invention consisting of improved forms and sections of a crystallized concrete material which may be assembled in the proper relation for the reception of a plastic material and having the several features and advantages set forth in this specification.

It is also a design of the invention to construct the sections of the veneer with the metal reinforcements so arranged as to interlock and produce a rigid and substantial casing which shall constitute a mold for the operations of pouring, ramming, and otherwise packing and placing the cementitious material therein, for a completed wall or structure.

The principles herein related may be embodied into any suitable form and combination of parts, provided the elements thereof shall be so relatively proportioned and arranged as to perform the functions herein enumerated, and therefore, for the purpose of explanation and to render the invention more intelligible, a preferred form thereof, having the proper correlative parts, is shown in the accompanying drawings, whereon—

Figure 1 is a perspective view of the veneer section ready to apply in concrete construction, showing the ornamental front and the transverse bonds or tie rods, Fig. 2 shows a portion of the corrugated back for securing plaster, Fig. 3 is a sectional detail view of the veneer showing a bond member which unites the two layers of a veneer, Fig. 4 is a sectional and detail view of a modified form of the veneer having beveled edges, whereby adjoining and superposed sections are maintained in alinement prior to receiving the cementitious wall material, Fig. 5 is a sectional and detail view of a sec-

tion of veneer showing the method of uniting the transverse bonds and the reinforcing rods, and Fig. 6 is a perspective and detail view showing my invention applied to a concrete wall.

Similar characters of reference apply to like parts of the invention throughout the several views.

The embodiment of the invention illustrated in the drawings is especially adapted to form the outer shell or mold of a concrete structure and may consist of opposed sections 1 and 2, of veneer, preferably made of a fine grade of concrete material, and these may be varied to suit different requirements. Each section consists of an outer layer and an inner layer, or the sections which may be used to form the inside of a concrete wall may be modified to comprise a single layer. The outer layer 3, of section 1, is formed with an ornamental design 4, to imitate bricks, but any preferred design may be used, and similarly, outer layer 5, of section 2, may be provided with parallel ribs 6, which are adapted to secure plaster or other finishing material to the inside of a concrete wall. The sections are preferably made with stepped edges 7, which make more solid the completed concrete structure for which the said sections form the veneer. Each section of the veneer is provided with wire bonds 8 which firmly unite the two layers thereof. In constructing a section of veneer, the outer layer is first molded with said bond wires 8 projecting therefrom at intervals, and, before the same is hardened or set, vertical reinforcing rods 9 and horizontal reinforcing rods 10, are placed thereon and pressed into the semi-plastic material, the said reinforcing rods having transverse connecting bars 11 tied thereto, as shown in Fig. 5. The reinforcing rods are partly embedded in the outer layer, and before the same has become hardened or crystallized, the inner layer is formed thereon. Concrete reinforcements 12, are provided at each point where the transverse bars enters the veneer.

To assist in maintaining alinement of the adjoining sections when set up prior to placing concrete therebetween, the ends 13, of the horizontal reinforcing rods, project from the section of the veneer and engage with corresponding recesses 14 in the adjoining section.

In a modified form of the invention as shown in Fig. 4, the veneer sections are pro-

vided with beveled edges 15, which assist in maintaining the sections in alinement when set up into a mold form. This is of especial utility in constructing columns and 5 girders of concrete.

In Fig. 6 the invention as shown is applied to the construction of a concrete wall 16, which is provided with reinforcing rods 17 and 18. In constructing the wall with 10 this veneer, the outer layer of the veneer may be composed of a fine grade of material 19, for the exterior, a coarser grade of material 20, for the inner layer, and a still coarser grade of material 21 for the main 15 body of the wall.

Obviously my concrete veneer is capable of considerable modification within the scope of the invention, and therefore I do not wish to be limited to the specific construction shown and described. Various 20 modifications may be made as in the size and thickness of the plate sections, in the number of reinforcing rods, in the design of the ornamental front, and in the grade of 25 material used in construction. Where door and window openings occur, the veneer plates may be shaped accordingly, so that the forms may be brought up properly to the openings. Other details of construction 30 may comprise similar variations without departing from the spirit of my invention.

My invention is designed to be set up and used as a form or mold without additional securing means, and when so set up and the 35 cementitious material has been placed between the veneer walls formed by the opposed sections, the said material will harden or crystallize and form with the veneer an integral and homogeneous structure.

40 I claim as my invention:

1. A concrete veneer for concrete structures, comprising similar and opposed sections formed in plates, reinforcing rods disposed in said plates, transverse bars extending 45 between said plates and tied to said reinforcing rods, concrete reinforcements for

said transverse bars at their points of entrance to said plates, stepped ends on said sections, projections formed by said reinforcing rods extending from one of said 50 stepped ends and adapted to engage with corresponding recesses in the opposite stepped end, and beveled horizontal edges at the top and bottom of each section, said beveled edges interlocking with the corresponding edges of the adjoining sections, and said projections interlocking with recesses in the adjoining sections, substantially as set forth.

2. In a concrete veneer for concrete structures, an outer section comprising two layers formed together and into a plate, the outer layer of the outer section having an ornamental surface design, an inner section comprising two layers formed together and 65 into a plate, the outer layer of the inner section having parallel ribs to cause the adherence of plaster or finishing material thereto, vertical and horizontal reinforcing rods disposed in each section between the 70 layers and embedded therein, transverse bars connecting the opposed sections and tied to said reinforcing rods at their points of intersection, wire bond members arranged in and connecting the two layers of each section, and means for maintaining said sections in alinement and in a rigid set up position comprising stepped ends which are 75 adapted to overlap with the corresponding stepped edges of the adjoining section, and projections on one of said stepped ends which engage with corresponding recesses in the adjoining section, substantially as set forth.

In testimony whereof I have affixed my 85 signature to the foregoing specification, this 17th day of May, in the year 1912.

JOHN JOSHUA MILLER.

In the presence of—

J. W. MASTER,
F. M. KEENEY.
